US00D496105S1

(12) **United States Design Patent**
Walters et al.

(10) Patent No.: **US D496,105 S**
(45) Date of Patent: **** Sep. 14, 2004**

(54) **TOP FOR A MEDICAL EXAMINATION TABLE**

D473,312 S * 4/2003 Cook D24/183

(75) Inventors: **Richard S. Walters**, Cedar Grove, WI (US); **Jack A. DeBral**, Plymouth, WI (US); **Vanessa B. Parrish**, Milwaukee, WI (US); **Michael J. Marchant**, Franklin, WI (US)

* cited by examiner

(73) Assignee: **The Brewer Company, LLC**, Menomonee Falls, WI (US)

Primary Examiner—Stella Reid

(**) Term: **14 Years**

(74) Attorney, Agent, or Firm—Ryan Kromholz & Manion, S.C.

(21) Appl. No.: **29/190,941**

(57) **CLAIM**

(22) Filed: **Sep. 29, 2003**

The ornamental design for a top for a medical examination table, as shown and described.

(51) LOC (7) Cl. **24-01**

DESCRIPTION

(52) U.S. Cl. **D24/183**

FIG. 1 is a perspective view of a top for a medical examination table, showing our new design;

(58) Field of Search D24/183; 312/209; 5/600, 607, 610-612, 616, 617; 297/325, 327; D6/335, 367

FIG. 2 is a right side elevation view thereof, the left side being a mirror image thereof;

(56) **References Cited**

FIG. 3 is a front elevation view thereof;

U.S. PATENT DOCUMENTS

FIG. 4 is a rear elevation view thereof;

D202,963 S * 11/1965 Dailey D24/183

FIG. 5 is a top plan view thereof; and,

FIG. 6 is a bottom plan view thereof.

1 Claim, 2 Drawing Sheets
